(57) **CLAIM**

The ornamental design for an inspection gauge for coordinate measuring machine, as shown and described.

DESCRIPTION

FIG. 1 is a front, right-side, top perspective view of the inspection gauge for coordinate measuring machine, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a rear, right-side, bottom perspective view thereof; and,

FIG. 9 is a cross-sectional view taken along line 9-9 in FIG. 2.

The evenly-spaced-dashed lines depict internal parts of the inspection gauge that form no part of the claimed design. The long-short-dashed lines depict the cross-section location and form no part of the claimed design.
